UNITED STATES PATENT OFFICE.

WILLIAM RICHARD ST. CLAIR, OF MCKENZIE, TENNESSEE.

LEVEL, PLUMB, AND ANGLE-GAGE.

SPECIFICATION forming part of Letters Patent No. 352,276, dated November 9, 1886.

Application filed June 3, 1886. Serial No. 204,071. (No model.)

To all whom it may concern:

Be it known that I, WILLIAM RICHARD ST. CLAIR, a citizen of the United States, residing at McKenzie, in the county of Carroll and State 5 of Tennessee, have invented a new and useful Improvement in Level, Plumb, and Angle Gages, of which the following is a specification.

This invention is an improved level, plumb, 10 and angle-gage; and it consists in the peculiar construction and combination of devices, that will be more fully set forth hereinafter, and particularly pointed out in the claims.

In the drawings, Figure 1 is an elevation of a 15 combined level, plumb, and angle-gage embodying my improvements. Fig. 2 is a top plan view of the same. Fig. 3 is a vertical section taken on the line *x x* of Fig. 2. Fig. 4 is a similar view taken on the line *y y* of Fig. 2. Fig. 5 20 is an elevation of the apparatus, looking on the reverse side from that shown in Fig. 1, and standing in a vertical position.

A represents a suitable frame or case, which is provided with a top, B, and sides C, made 25 of glass or other transparent material. In the center of the case or frame is a vertical standard, D, having at its upper end a horizontal rearwardly-extending arm or plate, E. A similar plate, F, is at the lower side of the standard, 30 immediately under the plate E. On the front side of the standard D, and at a suitable distance therefrom, is a vertical standard, G.

H represents a horizontal shaft, the ends of which are journaled in the standards G and D, 35 the said shaft being located transversely in the center of the case or frame. From the lower side of the shaft H depends a vertical rod, I, and from the lower end of the said rod extends a semicircular curved rod, K, the 40 arms of which extend in opposite directions from the rod I, and are provided with screw-threads. On the threaded arms K are secured weights L, which by reason of the screw-threads on the said arms may be so adjusted 45 as to cause the shaft I to be always maintained in an absolutely vertical position. To the front end of the shaft H is attached an index-hand, M, which swings around a graduated dial, N. The said dial is provided with two concentric circles drawn from the center of the 50 shaft A, and graduated and numbered to indicate the degrees, as shown in Fig. 1.

P represents a vertical shaft, which is journaled between the plates E and F, and to the upper end of the said shaft is attached a counterbalanced pointer or hand, R, the outer end of which sweeps over the horizontal dial S, that is attached to one end of the case or frame. In the center of the said dial is indicated a point, S', at which the hand R stops when the frame 55 or case is in a perfectly horizontal position, and from either side of the said point S' are described segments divided into degrees and fractions of degrees as far as the width of the case or frame will permit. One side of the 60 face of the dial S, on the right-hand side of the point S', is marked "High," and the other side of the said dial is marked "Low." From the lower end of the vertical shaft P extends a horizontal arm, T, the outer end of which is 65 provided with a slot.

U represents a pendulum-rod, the upper end of which is pivoted in opposite sides of an opening made in the plate E, and the lower end of which passes through the slot t, and is 70 thereby connected to the arm T. Near the lower end of the pendulum-rod is a weight, u, and from opposite sides of the said rod extend the curved arms of a rod, u', the said arms being screw-threaded and provided with adjustable weights u'', similar to the arms K and the weights L of the shaft H. By adjusting the weights u'' the pointer R will be caused to stop at the point S' of the scale S, when the case or frame is exactly level, as hereinbefore described. By thus providing the case or frame 75 with the dials N and S, arranged at right angles to each other, and the weighted index-hands M and R, adapted to swing over the said dials, it will be readily understood that 80 the angle at which the case or frame is supported will be indicated with exact certainty, one of the hands serving to correct any inexactness of the other.

V represents a long pendulum-rod, one end 85 of which is pivoted in the case or frame under the dial S. The said rod extends through the said frame or case, and its lower end is provided with a pointer, V', which swings over a graduated card, W. Across the lower end of the pendulum-rod V extends a transverse horizontal rod, X, the arms of which are screw-threaded and provided with adjustable weights Y, by means of which the pendulum will be 90 95 100

caused to stop at the point Z of the card W, when the case or frame A is maintained in a perfectly vertical position, thus serving the purpose of a plumb.

5 Having thus described my invention, I claim—

1. The case having the dials N and S, arranged at right angles to each other, the weighted index-hands M and R, adapted to swing over the said dials, the pendulum-rod V, pivoted at one end of the case and having the pointer V', and the graduated card or scale Z at the opposite end of the case, over which the pointer V' swings, substantially as described.

2. The combination, in a level, of the shaft P, having the arm T and the index-hand R, with the weighted pendulum-rod U, engaging with the arm T, for the purpose set forth, substantially as described.

20 In testimony that I claim the foregoing as my own I have hereto affixed my signature in presence of two witnesses.

WILLIAM RICHARD ST. CLAIR.
